[57] CLAIM

The ornamental design for combined hair clipper, base and accessories therefor, as shown and described.

DESCRIPTION

FIG. 1 is a perspective view of a combined hair clipper, base and accessories therefor showing my new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a perspective view of the clipper alone;

FIG. 7 is a top plan view thereof;

FIG. 8 is a rear elevational view thereof;

FIG. 9 is a left side elevational view thereof;

FIG. 10 is a front elevational view thereof;

FIG. 11 is a bottom plan view thereof;

FIG. 12 is a perspective view of the base and accessories therefor;

FIG. 13 is a top plan view thereof;

FIG. 14 is a front elevational view thereof;

FIG. 15 is a bottom plan view thereof;

FIG. 16 is a right side elevational view thereof;

FIG. 17 is a rear elevational view thereof; and

FIG. 18 is a left side elevation view thereof.
